UNITED STATES PATENT OFFICE.

FREDERICK YEISER, OF LEXINGTON, KENTUCKY.

INSTRUMENT FOR TAKING ALTITUDE OF THE SUN.

Specification of Letters Patent No. 22,913, dated February 8, 1859.

To all whom it may concern:

Be it known that I, F. YEISER, of Lexington, in the county of Fayette and State of Kentucky, have invented a new and useful 5 Instrument for Determining the True Meridian; and I do hereby declare that the following is a full, clear, and exact description of the same, reference being had to the annexed drawings, making a part of this specification, in which—

Figure 1, is a side elevation of my instrument, and Fig. 2, is a plan or top view of the same.

Similar letters of reference in the two figures indicate corresponding parts.

This invention consists in determining the plane of the meridian at any time in the forenoon or in the afternoon, by means of a spirally slotted cylinder which is attached to a 20 horizontal rotary frame in such a relation to a vertical pin and to a line which is strongly defined on the upper surface of the frame and which is provided with a toothed sector which gears into cogs on the top of a stationary disk, in such a manner that when 25 this cylinder is placed in such a position that the ray of the sun passes through the inner end of the spiral slot, and when the frame is now slowly rotated on its axis, the ray of 30 the sun ceases to pass through said spiral slot at that moment when the plane which is determined by the above named vertical pin and by the strongly defined line on the upper surface of the rotary frame coincides 35 with the plane of the meridian.

To enable others skilled in the art to fully understand and construct my instrument, I will proceed to describe it.

The moving parts of the instrument rest 40 on a circular plate A, of metal or other suitable material, having an upright shaft B, permanently fixed in its center, to the upper end of which is secured a horizontal circular plate or disk C, from the center of which 45 rises a vertical wire rod D, and a strongly defined line, 1, 2, is made over the surface of the disk C, radially from its center to its periphery. On the top of the base plate A, and between it and the disk C, is arranged a 50 rectangular frame E, consisting of two parallel horizontal bars E', E', through an opening in the center of which the upright shaft B, loosely passes, and which are connected together at their ends by blocks E'', 55 in such a manner as to enable said frame to freely traverse around said upright shaft.

Near one end of this frame is erected a vertical standard F, on the side of which, and flush with the side of the frame, is fastened a projecting piece F', and near the opposite end of said frame and at one corner of the same is fixed the vertical wire rod or pin G, from the base of which and parallel with the side of the frame, is drawn a black or otherwise strongly defined line, 3, 4, similar 60 in every respect to the radial line 1, 2, on the surface of the disk C.

To the upper end of the vertical standard F, is jointed by a horizontal screw rod or bolt, upon which it turns, a block or hub H, 70 on the face of which is secured the toothed sector I, which gears into a series of pins or cogs J, which are attached to the upper surface of the disk C, and which extend segmentally a little more than one-quarter 75 of its circumference.

The block or hub H, is provided with a shaft H', which extends radially from one end of the same, and it fits exactly into an opening in the inner or lower end of a cylinder L, provided with a clamp screw M, which presses against the shaft H'. The cylinder L, is bisected by a spiral slot K, which extends nearly from one end of the cylinder to the other, and which forms part 80 of a turn of a right handed screw thread, the pitch of which would be about double the length of the cylinder. This slit divides the cylinder in two parts of exactly the same size, so that whenever a transverse section 85 of the cylinder at right angles to its axis is taken, the slit appears in a straight line passing through the center of said section, as represented in Fig. 1, in black and in Fig. 2, in red outline.

The operation is as follows. The instrument is first leveled and turned until the shadow of pin D, covers the line 1, 2, and the cylinder L, is brought into a horizontal position and turned until the ray of the sun passes through that portion of the slit K, which is nearest to the end of the hub H, and in this position the cylinder L, is fastened by means of the set screw M. If now the frame E, be slowly rotated in the direction in which the sun travels (the whole operation must be accomplished, of course in such a space of time that the yearly motion of the earth has no influence on the observation) the cylinder L, which is rigidly attached to the frame E, begins 100 to move with this frame around the cen- 105 110

ter B, and at the same time it begins to rise by the action of the toothed sector I, and the cogs J, on the disk C, and the ray of the sun will cease to pass through the slit K, just at that moment, when the plane passing through the pin G, and the line 3, 4, coincides with the meridian, and if the instrument be left in this position, the shadow of the pin G, will cover the line 3, 4, at the moment the sun passes through the meridian. It will be noticed, that the distance over which the frame E, has to be moved depends upon the azimuth of the sun at the time of the observation, and the distance to which the cylinder L, rises, by this rotating motion, upon the corresponding altitude of the sun. Suppose it be 9 o'clock a. m., then the sun has to travel over an arc of 45 degrees in the parallel circle in which it appears to move at the time of the observation, in order to come into the plane of the meridian, and as the axis of the cylinder L, is at right angles with the edge of the frame E, and with the line 3, 4, it will be necessary in order to get the ray of the sun to pass through the inner portion of the slit K, to turn the base-plate A, to such a position that the plane passing through the line 3, 4, and through the pin G, makes an angle with the plane of the meridian which is expressed by the azimuth of the sun at the time of the observation. If the frame E, be now turned in the direction in which the sun travels, the cylinder L, will be brought in such a position that the ray of the sun can not pass any more through the slit K, as soon as the frame has been turned over an arc equal to the azimuth of the sun at the time of the observation, and the plane passing through

the pin G, and through the line 3, 4, will coincide with the plane of the meridian at the moment in which the ray of the sun ceases to pass through the slit K.

It is obvious that an observation may be taken at any time in the forenoon, and the time when the sun passes through the meridian may be thus determined, if the instrument is brought to such a position that the plane G, 3, 4, coincides with the plane of the meridian, as in this case the shadow of the pin G, covers the line 3, 4, at the moment in which the sun enters the meridian.

In order to make the instrument available for observations in the afternoon, it is necessary to arrange the slit K, in such a manner that it forms a part of a left-handed screw thread, all other parts being exactly the same, and an observation may then be taken at any time in the afternoon in the same manner which has been described.

Having thus described my invention, what I claim as new and desire to secure by Letters Patent, is—

1. The arrangement of the spirally slotted cylinder L, on a rotary frame E, in such relation to a pin G, and to a strongly defined line 3, 4, that it operates substantially as and for the purposes specified.

2. And, in combination with the rotary frame E, I also claim operating the cylinder L, by means of a toothed sector I, which gears into cogs J, which are attached to the stationary disk C, in the manner and for the purpose substantially as described.

FREDERICK YEISER.
